HANDLE FOR A SWAB FOR CLEANING TOILET BOWLS OR THE LIKE

Earnest L. Bennett, Indianapolis, Ind., assignor to J. I. Holcomb Manufacturing Company, Inc., Indianapolis, Ind., a corporation

Filed Oct. 20, 1958, Ser. No. 53,044

Term of patent 14 years

(Cl. D9—2)

Fig. 1 is a right side elevational view of an handle for a swab for cleaning toilet bowls or the like showing my new design;

Fig. 2 is a top plan view thereof;

Fig. 3 is a bottom plan view thereof;

Fig. 4 is a front elevational view thereof;

Fig. 5 is a fragmentary elevational view of the upper right hand corner of the top area of the ornamentation in Fig. 2 on an enlarged scale; and

Fig. 6 is a rear elevational view of the handle the front portions being omitted for convenience of illustration.

I claim:

The ornamental design for a handle for a swab for cleaning toilet bowls or the like, as shown.
